SLIDE BUCKLE

Robert J. Hodge, West Haven, Conn., assignor to
The American Buckle Company, West Haven,
Conn., a corporation of Connecticut

Application May 9, 1933, Serial No. 670,175

5 Claims. (Cl. 24—184)

This invention relates to slide buckles, particularly such buckles as include a pivoted clamping plate or lever.

In such buckles as now generally constructed, wherein the buckle frame is composed of a continuous length of material, usually wire, bent to desired form, the ends of this length of material are connected by means of a sleeve or by the clamping plate or lever. However, it has been found desirable to provide in buckles of this character rigidity and strength which cannot be obtained by these methods of connecting the ends of the length of the material, and one object of this invention is to provide a slide buckle in which the ends of the length of material are directly and rigidly connected with each other to form a continuous, uninterrupted, one-piece frame.

Another object of the invention is to apply the pivoted clamping plate or lever to a member or bar of this frame in such a manner that it may be positioned axially thereon by means of a protuberance or projection forming a part of such frame member.

A further object of the invention is to make possible the use of a clamping plate or lever of a single predetermined appropriate width with slide buckles of various widths by virtue of the positioning of the clamping plate or lever in the manner described.

The invention comprises a slide buckle having a frame composed of a single piece or length of material bent to appropriate form and including a bar in which the ends of the piece of material are arranged in abutting relation and appropriately joined together or interconnected to make the frame of uninterrupted one-piece construction, and a clamping plate or lever pivotally applied to the bar and provided with means for cooperation with a protuberance or projection formed on the bar, preferably at the point of junction of the ends of the piece of material forming the frame, as described, for locating the clamping plate or lever axially of the bar and hence laterally of the slide buckle, all as will be explained hereinafter more fully and finally claimed.

In the accompanying drawing illustrating the invention, in the several figures of which like parts are similarly designated, Figure 1 is a front view of a fragment of a strap, such as a fabric overall suspender strap with a slide buckle, having the characteristics of a combined buckle and button loop, applied thereto in operative position. Fig. 2 is a front view of the combined

slide buckle and button loop of Fig. 1 detached and with the clamping plate or lever raised. Fig. 3 is a back view of the buckle as illustrated in Fig. 2. Fig. 4 is a view of the buckle frame. Fig. 5 is a view of the clamping plate or lever before it is bent for application to the top bar of the buckle. Fig. 6 is an enlarged fragmentary sectional elevation showing the top bar of the buckle with the clamping plate or lever in preliminary bent form partially applied thereto. Fig. 7 is a view similar to Fig. 6 but showing the clamping plate or lever in completed pivotally attached condition. Fig. 8 is a view similar to Fig. 1 but illustrating a slide buckle of greater width than that illustrated in Fig. 1 and omitting the button loop, a button loop of conventional type being shown applied to the looped end of the strap. Fig. 9 is a side elevation of the parts shown in Fig. 8. Fig. 10 is a view similar to Fig. 9 but illustrating a different mode of threading or attaching the strap to the slide buckle. Fig. 11 is a view similar to Fig. 2, but illustrating the slide buckle of Fig. 8.

Referring particularly to Figs. 1 to 7 inclusive, it will be seen that the combined slide buckle and button loop illustrated therein is formed of a single piece of material, such as relatively stiff wire, bent to such form as to provide a button loop 1, a bottom bar comprising the portions 2, 2 which are connected with the loop 1, a divided intermediate bar comprising the bends 3, 3, the ends of which are spaced apart as indicated at 4, and a top bar 5 which includes the ends of the piece of material of which the frame is formed appropriately joined, as by butt-welding to produce an uninterrupted, integral, rigid frame. Where the ends of the wire are joined in the top bar 5, a protuberance or projection 6, preferably of annular form, is produced. The arrangement of the top, intermediate and bottom bars is such as to provide between them suitable spaces for the reception of a strap.

The clamping plate or lever is formed from a blank of sheet metal, or other appropriate material, substantially of the form illustrated in Fig. 5, so shaped at one edge as to provide a finger piece 7 of ornamental and attractive contour, and having its opposite edge provided with clamping teeth 8. In its central longitudinal portion and substantially centrally of its longitudinal vertical axis the plate is formed with a slot 9. This plate is preliminarily bent transversely substantially to U-shape, as illustrated in Fig. 6, with its slot 9 lying across the bend 10, and when the plate has its bend 10 moved into engagement with the top

- bar 5 of the buckle frame, and is struck down, as indicated at 11, Fig. 7, to embrace the top bar, the walls of the slot 9 will embrace the protuberance or projection 6 and will locate the plate axially of the top bar 5 and hence laterally of the buckle frame. As thus assembled the toothed portions of the plate will stand off from the body of the plate, as shown in Fig. 7, so as to present the teeth in position effectively to engage the strap.
- 10 In order that the clamping plate or lever may conform approximately to the curve of the strap 12 when the latter is threaded through the buckle, it is curved as clearly shown in Figs. 6 and 7.
- 15 In order that the slide buckle may be given a good hold upon the strap 12, particularly after the strap has been laundered and has become relatively flimsy or soft, the intermediate bar formed by the bends 3, and portions of the button loop 1, may be serrated, grooved or otherwise appropriately roughened upon both sides, as indicated at 13, or substantially in the manner disclosed in my copending application, Serial No. 624,566, filed July 25, 1932 (Patent No. 1,936,057, granted November 21, 1933).

As hereinbefore indicated, it is intended that the ends of the wire be joined substantially centrally of the top bar 5 by butt-welding, preferably by electric butt-welding in a well-known manner, and the characteristics of the welding process make it possible to control the annular extension of the projection or protuberance 6 to such degree as to make the projection or protuberance effective for cooperation with the walls 35 of the slot 9 of the clamping plate or lever to prevent undue shifting of the latter laterally of the buckle.

Where the slide buckle takes the form of a combined buckle and button loop as illustrated in Fig. 1, the strap 12 is threaded through it, in the customary manner, by passing the strap end 14 through the space provided between the top bar 5 and the divided intermediate bar 3, 3 from back to front, and then between the intermediate bar and the bottom bar 2 from front to back, so that it underlies the button loop 1. With the strap thus threaded, the slide buckle may be adjusted longitudinally thereof, and when appropriate adjustment is obtained, the clamping plate or lever may be turned to the position illustrated in Fig. 1, and in this turning its teeth 8 will impinge upon the strap and force the same into intimate engagement with the intermediate bar 3, 3, and the serrated or roughened surface thereof, to hold the buckle in fixed position on the strap.

The simple slide buckle illustrated in Figs. 8 to 11 inclusive, is the same, so far as its novel structural features are concerned, as the combined buckle and button loop just described. It is formed of a single length of material, preferably relatively stiff wire so bent as to provide a bottom bar 15, a divided intermediate bar formed by the bends 16, 16, the ends of which are spaced apart at 17, and a top bar 18 which includes the protuberance or projection 6' formed by the joining of the ends of the wire and serving the same purpose as the protuberance or projection 6 in locating the clamping lever or plate axially of the top bar 18 and laterally of the buckle. This 70 clamping lever or plate may be, and preferably is of the same size and structure as the clamping plate illustrated in Figs. 1 to 7 inclusive and is applied to the bar 18 in like manner, and although the simple slide buckle of Figs. 8 to 11 is wider than the combined slide and button loop previous-

ly described, and is adapted for cooperation with a wider strap 19, the plate or lever is properly located axially of the top bar 18 and properly functions with respect to the strap and to the divided intermediate bar 16, 16 by virtue of the engagement of the walls of its slot 9 with the protuberance or projection 6'.

This is an important characteristic of the invention. Due to the fact that the protuberance or projection 6 or 6' effectively positions or centers the clamping plate or lever laterally with respect to the buckle by its cooperation with the slot 9 of the clamping plate or lever, it will be apparent that only one size and type of clamping plate or lever need be provided for buckles of various widths, and that, therefore, one type and size of clamping plate or lever will serve, and the manufacturing cost of such buckles is measurably reduced.

Moreover, by directly uniting the ends of the piece of material of which the frame is formed and thus dispensing with sleeves or other applied connecting means, the number of parts used in constructing the buckle is reduced, the assembling operation simplified, and the cost of production lessened.

The bottom bar 15 and the divided intermediate bar 16, 16 of the simple slide buckle of Figs. 8 to 11, are preferably provided, on their fronts and backs, with serrated, grooved or otherwise appropriately roughened surfaces for the purpose of giving the slide buckle a better hold upon the strap, as previously described.

The strap 19 may be threaded through the slide buckle as illustrated in Fig. 9, or its end may be provided with a loop 20 connected with the divided intermediate bar by passing a portion of the loop 20 over one portion 16 of the intermediate bar and thereafter engaging the other portion of the loop with the other portion 16 of the intermediate bar in a well known manner.

From the foregoing, it will be seen that this invention makes possible the production of a one-piece continuous slide buckle frame of a number of desired types, two of which only are illustrated, 120 provided with a clamping plate or lever pivotally attached to the buckle by bending it around and into engagement with a selected bar thereof and located axially of such bar, and hence laterally of the buckle, and thereby centered thereon, 125 by engagement of means on the plate or lever with a protuberance or projection provided at the junction of the ends of the piece of material of which the buckle frame is formed.

Various changes and modifications are considered to be within the spirit of the invention and the scope of the following claims.

What I claim is:—

1. A slide buckle, comprising a frame made of a piece of material formed to appropriate shape and including a transverse top bar in which the ends of said piece of material meet, said ends secured together by butt-welding and the burr thus formed extending circumferentially around said ends and standing off from said bar and forming a circumscribing projection thereon, and a clamping plate bent transversely upon itself and embracing the top bar in the bend as a pivot and having an axial slot extending midway of its length and the walls of said slot engaging said projection on said bar and serving to position the plate centrally of the frame and hold it in such position, one portion of said plate having a finger piece for pivotally manipulating the plate and the opposite portion of said plate

- projecting angularly from the body of the plate and having its extremity serrated to afford means for engaging and holding a strap at any point of adjustment.
5. 2. A slide buckle, having a frame of wire folded between its ends to form a transverse upper bar the terminals of which are butted and welded together, the weld forming a burr extending circumferentially around said bar and standing off from it and forming a circumscribing projection thereon, and a clamping plate of sheet metal having a slot in its central longitudinal portion and said plate bent transversely across said slot and around and pivotally applied to the upper bar and the walls of said slot engaging said projection, said clamping plate being of less width than the inside transverse dimensions of the frame and applicable to frames of different widths.
10. 3. A slide buckle, having a frame of wire folded between its ends to form a transverse upper bar the terminals of which are butted and welded together, the weld forming a burr extending circumferentially around said bar and standing off from it and forming a circumscribing projection thereon, and a clamping plate of sheet metal having a slot in its central longitudinal portion and said plate bent transversely across said slot and around and pivotally applied to the upper bar and the walls of said slot engaging said projection, said clamping plate being of less width than the inside transverse dimensions of the frame and applicable to frames of different widths.
15. 4. A slide buckle, having a frame of wire folded between its ends to form a transverse upper bar the terminals of which are butted and welded together, the weld forming a burr extending circumferentially around said bar and standing off from it and forming a circumscribing projection thereon, and a clamping plate of sheet metal bent upon itself transversely and slotted longitudinally across such bend and straddling said upper bar, the walls of said slot engaging said projection to center the plate within the frame, said plate having one portion curved inwardly toward the body of the plate and constituting a finger piece and the other portion standing off angularly from the body and provided with a toothed edge to grip a strap threaded through the buckle, the finger piece when in clamped position overlying the toothed portion.
20. 5. A slide buckle, having a frame of wire folded between its ends to form a transverse upper bar the terminals of which are butted and welded together, the weld forming a burr extending circumferentially around said bar and standing off from it and forming a circumscribing projection thereon, and a clamping plate of sheet metal bent upon itself transversely and slotted longitudinally across such bend and straddling said upper bar, the walls of said slot engaging said projection to center the plate within the frame and position it laterally within the frame, said plate having one portion curved inwardly toward the body of the plate and constituting a finger piece and the other portion standing off angularly from the body and provided with a toothed edge to grip a strap threaded through the buckle.
